FORGING PRESS

Heinrich Mergel, Dusseldorf, Germany, assignor,
by mesne assignments, to Schloemann Engi-
neering Corporation, Pittsburgh, Pa., a corpora-
tion of Delaware

Application June 28, 1939, Serial No. 281,601
In Germany July 9, 1938

3 Claims.

(Cl. 78—96)

The present invention relates to a forging press of the type in which the work is shaped in a series of operations, the die tools being changed after each operation and the blank placed between the top and bottom dies of another forming tool. This changing of the die tools renders it necessary to remove the work from the bottom die after each operation and to place it in position between the upper and lower dies of the next forming tool. The latter movement is advantageously carried out immediately upon the new bottom die being brought into position ready for the next operation. The object of the invention is to facilitate the running of presses of the kind described in such manner as to make the work of removing the blank or work from one die and placing it between the upper and lower dies of the next forming tool purely automatic, the essential feature of the invention consisting in rendering the operations on the press useful for carrying out the operation hereinbefore described.

One construction of press according to the invention is illustrated, by way of example, in the accompanying drawings in its application to a press of the vertical column type for the production of rotary bodies, such as car wheels, or bodies of irregular shapes, the depression in the finishing die corresponding to the relief in the work sought. The various figures of the drawings all show respectively one half of the press in front elevation with parts in section.

Fig. 1 shows the forging press with the cross-head carrying the upper die in the lowest position of its travel and the upper die impressed on the work blank.

Fig. 2 shows the crosshead raised into a second position far enough to clear the upper die from the work blank, without laterally displacing the finger clamps to grip the work blank.

Fig. 3 shows the crosshead raised into a third position a little farther to cause lateral displacement of the finger clamps to grip the work blank.

Fig. 4 shows the crosshead raised still further into a fourth position which is the uppermost position of its travel, to raise the finger clamps as they grip the work blank, free of the bottom die, so that both dies can be changed, and

Fig. 5 shows the first step in the lowering operation, with the crosshead lowered into a fifth position and the control rod disconnected from the crosshead to render the finger clamps inoperative with movement of the crosshead when the work blank is to be changed.

Referring to the drawings, the upper cross-head of the press is numbered 1 and the supporting base for the columns is numbered 2. The upper half of the die is carried on and adapted to move sideways, adjustably across the crosshead 4, which latter is guided for vertical reciprocation on the columns 3, while the bottom die 6 is adapted to move on the base. The pressing operation is effected by means of the hydraulic cylinder 7 working in conjunction with the plunger 8, which is connected to the crosshead 4. The blank to be pressed is numbered 9. The press is fitted with a two part clamping device, of which the two halves (the part illustrated being numbered 10 and the other half being in the right unillustrated half of the apparatus) are adapted to move towards and away from each other in the horizontal plane on supporting brackets 11 toward and away from blank 9. Each bracket 11 carries a rocking lever 12 which rotates about a pivot 13 and is hinged at 13¹ to one of the movable halves 10 of the clamp. The clamping device is caused to close and open by moving the levers 12 respectively towards and away from each other. Each lever 12 is subject to the action of a weighted lever 14; these weighted levers tend to maintain the halves of the clamp apart. Each bracket 11 rests upon a plunger 15, which is under a constant pressure of water in the cylinder 16. The plunger 15 is carried at the end of a piston rod 17 having at its opposite end adjustable stop nuts 18. The force exerted by the water in the cylinder 16 to force the plunger 15 upwards also lifts the sleeve 29, which is carried by the bracket 11 and whose upper annular surface presses against the cross-head 4. Pivoted to the lever 14 at 19 is a rod 20, which carries a resilient stop 21 adapted to rest on an outward projecting extension 22 from the crosshead, the extension being fork-shaped in cross-section. The rod 20 forms a knee-joint with a lever 23, being coupled thereto by a slot connection or the like. The lever 23 is adapted to oscillate about a pivot 24, and rigidly connected to it is a lever 25 which is pivotally connected to a second piston rod 26. The rod 26 has its upper end sliding in a primary cylinder 27 and its lower end sliding in a secondary cylinder 28. There is a constant water pressure in the secondary cylinder 28, while water in the cylinder 27 is arranged so that its pressure can be controlled.

The press operates in the following manner: Figure 1 shows a press after the completion of a pressing operation. If the upper die 5 is

raised by lifting of the crosshead 4, the latter takes with it the rod 20 by reason of the extension 22 engaging with the resilient stop 21. The water under pressure in the lifting plunger cylinders 16, forces the plungers 15, and thereby the brackets 11, upwardly the same amount as the amount the rod 20 moves upwardly. The effect is that the lifting movement of the brackets 11 brings the movable halves 10 of the clamp into the starting position vertically as shown in Figure 2. The upward movement of the brackets 11 ceases as soon as the nut 18 abuts against the lower end of the cylinder 16 (see Figure 2), but the rod 20 in continuing to move upwardly with the crosshead turns the levers 14 so that, as shown in Figure 3, the two halves 10 of the clamping device are moved towards one another to engage, and grip the work 9, which it will be observed has been freed from the upper half of the die due to the latter having been raised with the crosshead. While the halves of the clamping device are moving horizontally toward each other to grip the work, the brackets 11 and the sleeves 29 are stationary, so that the crosshead 4 will move away from the sleeve 29 as will be seen in Figure 3. As the rods 20 continue to rise with the crosshead, they will continue to raise the brackets 11, with the result that the work, gripped between the halves of the clamp, is raised clear of the under die 6 (see Figure 4). During the last-mentioned movement the brackets 11 have (as shown in Figure 4) been lifted away from the plungers 15. The machine operator can now change the die by replacing the previous two halves, the top and bottom dies 5 and 6 with new ones. The succeeding action of placing the work in the new die is carried out automatically by causing the working operations before described to be performed in the reverse order and backward by the lowering of the crosshead 4. Thus in this operation the clamping halves 10, 10 first of all move downward carrying with them the work. Immediately the brackets 11 engage the plungers 15, the lowering movement of the brackets is temporarily suspended, so that further lowering of the rods 20, causes the clamping parts 10 to separate, this action being facilitated by the weighted levers 14. The work is thus released from clamps 10 for shaping by application of 50 the new dies. Immediately these clamping parts 10 have been opened into the position shown in Figures 1 or 2, the crosshead 4 will come down and engage with the sleeve 29. Consequently further downward movement of 55 the crosshead 4 forces the plunger 15 downwardly against the resistance of the water under pressure in the cylinder 16. At the same time the various parts of the press revert to the position shown in Figure 1. Thereupon, the cycle of movements described above can be repeated.

In order to render the clamping device inoperative on the opening of the die for the changing of the work, the plunger in the cylinder 27 is subjected to water under pressure. The ef- 65

fect of this is to swing the lever 23 outwardly. At the same time the rod 20 is swung about pivot 19, causing the resilient stop 21 to be released from the extension 22 on the crosshead 4, as shown in Fig. 5. If the crosshead 4 be now lifted, the clamping device remains unaffected, the slotted connection previously referred to permitting the rod 20 to move axially. After the new work has been introduced into the press, lowering of the crosshead 4 will permit the rod 20 to return the position shown in Figure 1. Since pressure in cylinder 28 will swing the rod 20 inwardly to re-engage the stop 21 with the extension 22, the cycle of operations described can now be performed on the new work.

The invention is not confined to the construction of the apparatus described and illustrated, for it is concerned principally with the device which is controlled for gripping the work and removing it from one of the dies of the press.

I claim:

1. In a forging press for shaping a work blank, a vertical column, a crosshead, means for supporting said crosshead to be vertically movable and guideable on said column, a base supporting said column, a lower die mounted on said base, an upper die carried on said crosshead in register with said lower die, a projecting forked lug carried by said crosshead, a control rod, means for supporting said control rod vertically slidably and engageably with said forked lug, said control rod carrying a stop for engaging said lug, a bracket vertically displaceable on said column, a clamping finger horizontally displaceable on said bracket and adapted to engage a work blank positioned on said lower die, lever means pivotally mounted on said bracket and engageable with said finger for horizontal displacement thereof, said lever means further engaging said control rod for displacement therewith, and a sleeve vertically displaceably mounted on said column intermediate said crosshead and said bracket, said apparatus being so constructed and arranged that when said crosshead is in its top position said dies are separated and said work blank is supported therebetween clear thereof by said bracket and said finger and as said crosshead is lowered into successive lower positions, said blank is lowered to rest on said lower die and said finger is retracted clear of said lower die and said upper die is forced down to impress said blank.

2. A forging press according to claim 1, and disconnecting means adapted to disconnect said control rod and its stop from engagement with said forked lug, for rendering said rod and said bracket independent of movement of said crosshead for changing said work blank.

3. A forging press according to claim 1, and a plunger, and means for supporting said plunger resiliently vertically displaceably with reference to said base and engageably with said bracket in a depressed position of said bracket.

HEINRICH MERGEL.
